Primary Examiner — Cynthia Ramirez

(74) Attorney, Agent, or Firm — Knobbe, Martens, Olson & Bear, LLP

(57) **CLAIM**

The ornamental design for a trash can, as shown and described.

DESCRIPTION

FIG. 1 is a top, front, left-side perspective view of a trash can embodying our design;

FIG. 2 is a front elevation view thereof;

FIG. 3 is a rear elevation view thereof;

FIG. 4 is a left-side elevation view thereof, the right-side elevation view being a mirror image of the right-side elevation view;

FIG. 5 is a top plan view thereof; and,

FIG. 6 is a bottom plan view thereof.

All features illustrated in broken lines form no part of the claimed subject matter.

1 Claim, 6 Drawing Sheets# US D675,803 S
